LOYD SCRUGGS, OF OMAHA, NEBRASKA.

COMPRESSED-AIR SPRAY.

SPECIFICATION forming part of Letters Patent No. 721,752, dated March 3, 1903.

Application filed July 22, 1901. Serial No. 69,170. (No model.)

To all whom it may concern:

Be it known that I, LOYD SCRUGGS, residing at Omaha, in the county of Douglas and State of Nebraska, have invented certain useful Improvements in Compressed-Air Sprays; and I do hereby declare that the following is a full, clear, and exact description of the invention, such as will enable others skilled in the art to which it appertains to make and use the same, reference being had to the accompanying drawings, which form a part of this specification.

This invention relates to a new and novel improvement in compressed-air sprays.

15 The aim of my invention is to provide a coin-operated air-spray adapted to be used in theaters, churches, railway-cars, barbershops, dentists' offices, and, in fact, wherever it may be desired to have a cool spray of air. 20 In the accompanying drawings I have shown in Figure 1 a side view of a coin-controlled compressed-air spray. Fig. 2 shows a side view thereof with portions removed. Fig. 3 shows a detail of the movable and adjustable head, 25 while Fig. 4 shows an enlarged detail disclosing the arrangement of the air-controlled valve.

My invention embodies, essentially, a housing A of any suitable material and conformation, which is inclosed by means of a glass front C, held by means of the frame B. Extending into this housing A is a compressed-air pipe F, which is provided with an air-controlling valve the housing of which is marked 30 H, and is secured to the air-supply pipe F by any suitable means. Held within this valve-housing H is the valve-stem 15 of any ordinary construction. This valve projects, however, beyond the valve-housing H upon both 35 sides and has one of its ends provided with the slot x, while the remaining extending portion of this valve 15 has secured to it, by means of a suitable screw 17, a coil-spring 14, so that this valve 15 is in a normally closed 40 condition and being held under spring tension by virtue of the coil-spring 14, which has its remaining end coiled about a pin e, secured to the valve-housing H, as is shown in 45 Figs. 1 and 2.

50 Secured to the valve 15 is an incised disk

16, as shown more clearly in Fig. 2, which is provided with the removed portion Z, so as to form a seating into which normally drops and is held the spring-operated plunger-stem c.

Extending upward and beyond the housing A from the valve H is the pipe 7, which pipe 7 above is provided with the terminal valve-housing 4, within which is held the valve 3, which valve is provided with the removed portion b and enters into the hollow perforated head 2, provided with the perforations a, as is disclosed in Fig. 1.

It will be noticed in referring to Fig. 3 that the head 2 is secured at an angle to the stem 3, so that this stem 3 may be revolved to bring the face of the head 2 into various positions, so that the air-spray passing out of the openings a may be directed straight ahead or upward or downward. The valve 3 of this movable and adjustable head 2 is secured by means of the screw 6 and the interposed washer 5, as is usual in ordinary valve construction.

Extending from the tube 7 is the downwardly-turned elbow 8, and this elbow 8 is provided with a metal frame 9, within which is held the glass tube i, the metal frame 9 being in the form of a tube provided with the removed portions i, as is clearly shown. This 80 glass tube i is in air communication by means of the elbow 8 with the tube or pipe 7. Working within the glass tube i is a piston 10, which piston is suitably secured to the stem c, which stem c extends through the terminal 85 cap 1, closing the lower end of the glass tube i and suitably secured to the frame 9. Passing through this stem c below the cap 1 is a pin 13, and interposed between the piston 10 and the cap 1 is an ordinary spring 12 to 90 normally force this stem c upward to hold this stem c out of engagement with the incised disk 16, which forms a locking cam or keeper by means of which the air-supply valve 15 may be held in an open condition 95 when engaged by the stem c. To control the movement of this valve 15, I provide the valve-housing H with the pins 23 and 23', (referring now to Fig. 4,) the valve 15 being provided with the stop-pin 20, adapted to 100

come into engagement with the pins 23 and 23' to check the valve 15 in its open and closed position.

- 5 Positioned adjacent to and in alinement with the slotted end of the valve 15 is a key 25, which has a hub 25', extending through the side of the housing A, and this hub is provided with a registering incision, as indicated in dotted lines in Fig. 1, similar to the end of the stem 15, the incision of which is clearly shown in Fig. 4. The width and distance of these slots and their relative position are so adjusted that they nicely actuate a coin of a certain value, as indicated at V in Fig. 1. Positioned below the slotted end of the valve 15 and the slotted hub 25' are the pins 30 30, which are so positioned that they just hold the coin or token between them, so that anything smaller than the desired coin or token will drop between these pins 30 30, while a chute D, which terminates just above these slotted members 15 and 25', will not permit any coin or token of a larger size to be inserted into the chute D, extending beyond the housing A, as shown.
- 25 Positioned below the coin-holding members 15 and 25', is a suitable receptacle K, into which the coins eventually drop.

My air-spraying device may be attached to the back of a chair or may be held upright 30 in a suitable position by means of the supply-pipe F, which forms a standard and holder for the housing A, and this pipe F may be provided with a suitable foot, so that the same may be portable, permitting its being moved 35 from place to place within certain limits.

Connected to the pipe F is a suitable air-supply pipe leading from a tank within which the compressed air is held, the air being conducted to the pipe F by any suitable means.

- 40 Where the instrumentalities have been properly constructed, the operation of my device would be as follows: The air-supply valve H would be held in a normally closed position because of the spring 14. A suitable coin or token would then be placed within the chute and in passing through the same would fall within the incisions within the end of the valve 15 and the hub 25', being supported by means of the pins 30. As soon as the 45 coin had found lodgment it would form a connection between the handle 25 and the valve 15, and the operator would then turn the valve to open the same to permit the escape of the air through the pipe 7 and perforated 50 head 2. As soon as the valves were turned a suitable distance the air would rush through the elbow 8 and into the cylinder g and exert a pressure upon the piston 10 to counteract the tension of the spring 12, and so force the 55 end of the stem c into engagement with the incised keeper 16 to hold the valve 15 in an open condition, so that the air would readily escape through the perforations a. As soon as the operator released the handle 25 the 60 coin would fall out of the slots x into the receptacle K below. The operator would then

adjust the head 2 at a proper angle, so that the air would be blown into the operator's face.

In referring to Fig. 3, it will be noticed 70 that the stem 3 has the removed portion b, so that the air may readily pass through the opening b and into the head 2. In tilting the head 2, however, in one position the solid portion of the valve 3 would come over and 75 close the opening within the valve 4, so that by means of this movable and adjustable head 2 the air may be cut off, if desired.

In equipping a theater, for instance, with my air-spraying device the housings A could 80 be secured to the backs of all chairs excepting, say, the first row, so that the forward chair within each row would act as a standard for the rear chair, and the air could be conducted to the tubes F by any suitable 85 means. A main cock would be placed within the main supply-pipe and this be turned on so that all the tubes F would supply with air. After the performance or at the conclusion of any certain time the main supply-cock 90 would be turned off, which would cut off all the air-pressure within the tubes F, so that the pressure above the piston 10 would be removed, so that each piston 10 would at once be thrown upward to release the valves 95 15 to cut off the air-supply, so that all the connected spraying apparatus would be instantly disconnected and locked in turning off the pressure at a suitable main supply-point. As soon as the pressure were again turned on the 100 apparatus would all be in condition to be again operated by means of the coin.

I do not wish to be understood as desired to confine myself to the exact construction and arrangement of the instrumentalities as 105 shown, as certain changes may be made without departing from the spirit of my invention.

Having thus described my said invention, what I claim as new, and desire to secure by 110 United States Letters Patent, is—

In a spraying device of the character described the combination, with an air-supply pipe, of a valve secured intermediate of the ends of said pipe, a spring secured to said 115 valve to normally close the same and hold the same under spring tension, a seating within said valve, a branch pipe extending from aforesaid pipe, a piston working within said pipe provided with a projecting stem, said stem being adapted to work into aforesaid seating of aforesaid valve, a spring to normally force said piston inward to hold aforesaid stem normally out of engagement with said seating, and means to turn aforesaid 120 valve against its spring tension, said instrumentalities being arranged to operate substantially in the manner set forth.

LOYD SCRUGGS.
